DEVICE FOR GENERATING ARCS
OR THE LIKE

Eric H. Wang, Cincinnati, Ohio

Application March 17, 1949, Serial No. 81,993

3 Claims. (CL. 90—20)

1

My invention relates to a device and process for generating arcs of a radius which is so large that it is impossible or impractical to use the center of the arc as a pivot point.

In machining, engraving, and other purposes, it is often desirable to generate an arc with the tool wherein the chord or length of the arc is relatively short, but the radius of the arc extremely large, but where the center of the arc is so remote from the machine or engraving apparatus that it is impossible or impractical to use the center as a pivot about which to revolve an arm.

It is an object of my invention to provide a device for generating arcs of large radius to an accuracy sufficient for practical purposes which is located substantially on the arc being generated and without the necessity of any portion of the device projecting to or being connected to any center remote from the device.

It is a further object of my invention to provide a process and device for simply and readily generating arcs of sufficient accuracy for practical purposes which is quite simple to construct and maintain and which may be easily altered to generate arcs of different radii and different lengths.

While in the following drawings and description I will show and describe a device primarily for use with a planer or a milling machine, it is to be understood that this is merely exemplary of my process and device since the process and device may be used for many other purposes such as engraving, drawing, or any place where it is desirable to generate an arc of relatively large radius for practical and non-mathematical purposes.

These and other objects of my invention which will be set forth hereinafter or will be apparent to one skilled in the art upon reading these specifications, I accomplish by that certain construction and arrangement of parts of which I shall now describe an exemplary embodiment. Reference is made to the drawings in which:

Figure 1 is a sketch showing a near approximation to a circular arc generated by the tool of my device and a true circular arc of very large radius.

Figure 2 shows the movement of the work piece in reference to the tool whereby the arc is generated.

Figure 3 shows my device as applied to the table and bed of a planer in plane.

Figure 4 shows my device as applied to the table and bed of a planer in elevation.

2

Figure 5 shows my device as applied to a milling machine in elevation.

Briefly, in the practice of my invention, I have determined that a portion of the loop of a looped trochoid in its special case, an archimedean spiral, very closely approaches the true arc of a circle of substantial radius in referring to a relatively short chord or arc. I have determined that a trochoid can, for example, be generated by translating the work piece in a straight line, while at the same time rotating it through a certain rather small angle and that any tool which is stationary as to its position on the machine will describe in the work piece a part of the trochoidal curve.

The distance to be traveled and the angle through which the work piece must rotate while traveling this distance will be in a constant ratio for each case and will depend on (a) the distance 20 of the lowest point of the trochoid to the center of rotation of the work piece. This is equal to the distance of the points of contact of the tool to the straight line which the center of rotation of the work piece describes. (b) The radius 25 desired, and (c) the length of the chord between the end points of the arc desired.

The calculation is based on a trochoid which coincides in three points with the desired arc, preferably a point at or near each end of the 30 desired circular arc and an intermediate point. Computations actually performed show a deviation of only a few thousandths of an inch down to less than one thousandth of an inch at the place where the trochoid which is generated and the circular arc which is desired are furthest apart.

The deviation between the trochoid generated and the circular arc desired becomes smaller with increasing radius and relatively diminishing 40 chord. For an arc of 240 inch radius and a chord of 60 inches length, the deviation is less than .001 inch.

Figure 1 shows a piece of work 1 into which a circular arc 2 is to be cut. Points A and C as 45 well as intermediate B are identical with the arc 2 and the trochoid 3 which is generated and indicated by the broken line. The point of greatest deviation between the trochoid 3 and the arc 2 is at 4 and as heretofore pointed out is extremely small, and for practical purposes is negligible, diminishing as the radius increases.

The equation of the trochoid can be developed by using the equation of the involute to start with and in other ways mathematically well-known and may be determined for each indi-

vidual setting based on the radius of the arc to be cut or generated and the length of the chord.

In Figure 2, the starting position of the work piece 1 is shown at 5 and the end position of the work piece 1 is shown at 6. The position of the tool which is stationary is shown at 7. The rotating work holder is indicated at 8 and in Figure 2 rotates in a clockwise direction about the center 9 and the distance the tool holder 8 is translated is the distance between the centers 9-9 in Figure 2. The broken line 10 indicates the arc (trochoid generated) to be cut by the tool 7 and is shown completed at 10' in Figure 2.

Figures 3 and 4 show my device as applied to a planer having a reciprocating or translating table 11 and a stationary bed 12. The rotating work holder 8 is positioned on the table 11 and reciprocates with it. The work 1 is held in position by suitable clamps 13. The tool 14 is held by the normal tool holder 15.

A gear 16 mounted on a shaft 17 which rotates the work holder 8 about its center 9 by means of mechanism not shown is common in the art. A train of gears 18 runs from the gear 16 to a rack 19 which is mounted by means of brackets 20 to the bed 12.

From the above, it is apparent that by selecting gears of specific relative sizes for the gear train 18 the ratio of translation to rotation of the work 1 may be adjusted so that the tool 14 will generate a portion of a specific trochoid 10 in the work 1.

Figure 5 shows the application of my device to a milling machine having reciprocating or translating table 20 and a stationary base 21. The lead screw of the milling machine 22 is connected by gearing 18 to the shaft 17 which rotates the work holding table 8. The milling cutter 23 rotates to cut the material but does not move in a horizontal plane. The action is the same as that described in reference to the planer, that is, the ratio of the translation of the table 21 to the rotation of the work holding table 8 is covered by the gears 18 and is so adjusted that the tool 23 will generate the desired portion of the specific trochoid on the work 1.

While I have described my invention as applied to a planer or a milling machine, it is to be understood that I do not intend to limit myself specifically to these two machines since the application is adaptable to numerous other machine tools as well as engraving machines and other devices where it is desirable to have a tool or stylus

generate a portion of a trochoid or similar figure.

As is apparent, the device is relatively simple, rugged, and subject to complete control.

It is to be understood that modification may be made in my invention without departing from the spirit thereof. Having thus described my invention in an exemplary embodiment, what I claim as new and desire to secure by Letters Patent is:

- 10 1. In a planer or the like a rotatable work holder positioned on the reciprocating table of the planer with its axis of rotation perpendicular to the direction of reciprocation of the table, a rack associated with the stationary planer bed, a train of gears engaging the rack and the work holder for rotation thereof in fixed relation to the translation of the table and a stationary tool positioned over the work holder.
- 15 2. In a planer or the like a rotatable work holder positioned on the reciprocating table of the planer with its axis of rotation perpendicular to the direction of reciprocation of the table, a rack associated with the stationary planer bed, a train of gears engaging the rack and the work holder for rotation thereof in fixed relation to the translation of the table and a stationary tool positioned over the work holder, said train of gears being variable.
- 20 3. In a machine tool or the like, a stationary bed, a rack fixed on the bed, a reciprocating table on the bed, a rotatable work holder on said table having its axis of rotation perpendicular to the direction of reciprocation of the table, a single series of intermeshing gears, said gears being interconnected with the rotary work holder, the reciprocating table and the stationary rack, whereby said work holder is rotatable and the table reciprocable simultaneously.
